UNITED STATES PATENT OFFICE.

MORRIS OZLEK, OF PHILADELPHIA, PENNSYLVANIA.

LAMP-SUPPORT.

1,330,336.

Specification of Letters Patent. Patented Feb. 10, 1920.

Application filed May 29, 1919. Serial No. 298,358.

To all whom it may concern:

Be it known that I, MORRIS OZLEK, a citizen of the United States, residing at Philadelphia, in the county of Philadelphia and 5 State of Pennsylvania, have invented certain new and useful Improvements in Lamp-Supports, of which the following is a specification.

One object of my invention is to provide 10 an improved cluster top for standard lamps which can be quickly and easily made of metal, wood or other suitable material.

Another object is to construct my improved cluster top in such manner that it 15 will be neat and ornamental in appearance and efficiently serve for the purpose intended.

A further object is to so make my invention that, even though the cluster top is 20 made of wood or other nonmetallic material it will firmly hold under tension a shade mounted thereon and so that the parts which hold the shade will not readily become worn.

These objects, and other advantageous 25 ends which will be described hereinafter, I attain in the following manner, reference being had to the accompanying drawings in which—

Figure 1 is a sectional elevation showing 30 my improved cluster top attached to a lamp standard and illustrating how the same supports a shade,

Fig. 2 is a side elevation of my improved one-piece cluster top,

Fig. 3 is a sectional elevation taken on the line 3—3 of Fig. 2,

Fig. 4 is an inverted plan view showing my improved cluster top with the shade-retaining means thereon,

Fig. 5 is a fragmentary section taken on the line 5—5 of Fig. 1,

Fig. 6 is a perspective view of a spring tension plate which forms a part of my invention,

Fig. 7 is an enlarged sectional view taken on the line 7—7 of Fig. 6, and

Figs. 8 and 9 are perspective views showing modified forms of my improved tension plate.

Referring to Figs. 1 to 7 inclusive, 10 represents my improved cluster top which is made of a single piece of non-metallic material, such for example as wood, and is provided with a cylindrical cavity 11 which ex-

tends upwardly from its bottom surface 12 and stops short of the top surface 13. Holes

14 are drilled into the cluster top 10, preferably at an incline to the axis of the cylindrical cavity 11 and into these holes 14 are screw threaded sleeve couplings 15 to which 60 the electric lamp sockets 16 are screwed and secured by the usual set screws 17. The holes 14 intersect the cavity 11 between the surface 12 and the innermost surface 18.

A hollow standard 19 has a cylindrical 65 tenon 20 which fits within the cavity 11 and a shoulder 21 which abuts the surface 12 of the cluster top 10. The tenon 20 is locked to the cluster top 10 by means of a screw 22 which extends laterally through the side 70 of the cluster top and into the tenon 20, as clearly shown in Figs. 1 and 5.

The cavity 11 provides a space for the splicing 23 of the electric conduit wires 24 which pass upwardly through the standard 75 19 and have branches 25 which lead through the respective holes 14 and sleeve couplings 15 to the lamp sockets 16.

The cluster top 10 has a hole 26 extending downwardly from the top surface 13 into the cavity 11 to provide an entrance for a screw 27 which is attached to a knob 28. The inner end of the screw 27 projects into the cavity 11 and fits a screw threaded hole 29 in a spring plate 30. The spring plate 85 30 is preferably made of spring steel and is of such length that it must be bowed in order to be extended transversely across the cavity 11.

The ends 31 of the plate 30 engage the 90 side wall of the cavity 11 and also abut the inner surface 18 of said cavity. In other words, the plate 30 occupies a position at the innermost portion of the cavity 11 and when placed therein is bowed downwardly 95 in the form of a part of an elliptic spring; there being a space between the surface 32 of the plate 30 and the surface 13 of the cavity 11.

A shade 33 has a ring 34 adapted to rest 100 on the upper surface 13 of the cluster top 10 and the screw 27 extends through the ring 34 so that the knob 28 abuts the upper surface of the ring. When the knob is screwed downwardly it compresses the ring 105 34 of the shade between it and the surface 13 of the cluster top and at the same time pulls the spring plate 30 toward the surface 18 and thereby places the spring plate under tension and causes the ends 31 to press 110 against the side wall of the cavity in opposite directions. The shade is thereby

clamped to the cluster top 10 under tension, and since the screw 27 and spring plate 30 are made of metal, it is immaterial whether the hole 26 in the cluster top 10 becomes 5 worn; the clamping action of the parts will always remain and the shade will not vibrate or become loose.

In Fig. 8 I have shown a spring plate 35 which has flanges 36 at its opposite ends 10 which can be used if preferred, since the ends will not readily dig into the wood and become loose if it is desired for use on a soft wood cluster top.

Fig. 9 shows a construction of a spring 15 plate 37 which has teeth 38 on its opposite edges, said teeth projecting from a flange 39. With this construction, it is immaterial whether the teeth penetrate the wood, the flanges 39 forming stops to limit the 20 extent of longitudinal separation of the ends of the plate. In other words, if the teeth 38 extended entirely into the wood, the flanges will form a stop to limit further 25 piercing of the plate into the wood so as not to lose the spring action of the plate. By making my invention as above described, the parts can be quickly put together and there are no undesirable partings on the upper portion of the cluster top, 30 it merely being necessary to use a single laterally extending screw which is located below the entrance portions of the coupling sleeves with the sockets.

While I have described my invention as 35 taking a particular form, it will be understood that the various parts of my invention may be changed without departing from the spirit thereof, and hence I do not limit myself to the precise construction set 40 forth, but consider that I am at liberty to

make such changes and alterations as fairly come within the scope of the appended claims.

Having thus described my invention, what I claim as new and desire to secure by 45 Letters Patent is:—

1. A lamp support including a cluster top having a cavity therein; a normally bowed thin spring plate fitting within said cavity and having a hole therein; and a 50 knob having a clamping screw thereon and extending downwardly through said cluster top into said cavity and fitting said hole in said spring plate, said hole being of less diameter than the outer diameter of the 55 clamping screw whereby the clamping screw will screw into said hole and thereby place tension on said clamping screw to draw said knob toward the cluster top so that a portion of a shade can be held in 60 firm engagement with said cluster top; substantially as described.

2. A lamp support including a cluster top having a cavity therein; a spring plate fitting within said cavity and having a hole; 65 a knob; and a clamping screw secured to said knob and extending through said cluster top and fitting said hole in said spring plate, said spring plate being bowed within said cavity and having its ends abutting 70 the side of said cavity; substantially as described.

In testimony whereof I have signed my name to this specification in the presence of two subscribing witnesses.

MORRIS OZLEK.
